UNITED STATES PATENT OFFICE.

WALLACE M. WEEKS AND JOHN A. PEASE, OF SKANEATELES, NEW YORK.

METHOD AND APPARATUS FOR MAKING BOTTLE CLOSURES.

Application filed January 7, 1926. Serial No. 79,814.

To all whom it may concern:

Be it known that we, WALLACE M. WEEKS and JOHN A. PEASE, citizens of the United States, residing at Skaneateles, in the 5 county of Onondaga and State of New York, have invented certain new and useful Improvements in Methods and Apparatus for Making Bottle Closures, of which the following is a specification.

10 This invention relates to the manufacture of bottle closures or caps, from paper stock, and designed particularly for closing and sealing the mouths of ordinary milk bottles.

15 The invention especially relates to the method of making the said caps, and particularly to the mechanical means for producing the same.

20 Present invention has in view the employment of certain methods, steps, means, mechanisms and apparatus for the practical and rapid manufacture of the bottle closures, which are hereinafter clearly shown, described, and claimed.

25 In the accompanying drawings, to which reference may be had for a clearer and more comprehensive understanding of our invention, we have illustrated the various steps which may be employed in the construction of a bottle closure embodying our invention, 30 and also the means by which said steps are effected, but it should be understood that the shape or pattern of the blanks from which the closure is constructed, and also that the steps described herein may be varied, within 35 the scope defined by the claims.

Figure 1 is a vertical section, taken on line 1—1 of Fig. 5; showing the blanks, which comprise the two-part closure, and the parts of the mechanism in their respective 40 positions to start the molding of one of the closures. Fig. 2 is a similar section; showing the blanks brought together at the pressing position, and the larger blank gripped by the corrugating members. Fig. 3 is a 45 similar section; showing the primary molding operation. Fig. 4 is a similar section; showing by full and dotted lines the final folding and pressing of the body blank, and the finished cap ready to be ejected, as in 50 Fig. 1. Fig. 5 is a top plan view of the molding apparatus, shown in Figs. 1, 2, 3, 4. Fig. 6 is a reduced rear side elevation of the complete apparatus; showing the various driving means. Fig. 7 is a plan view of 55 the pliable paper disc from which the main body of the cap is formed. Fig. 8 is a top

plan view of completed cap. Fig. 9 is a top plan view of the reinforcing disc. Fig. 10 is a bottom end view of the inner sleeve, which cooperates with stationary parts of the die, for partially forming the convex flange of the cap. Fig. 11 is a bottom end view of the upper tension-controlled member employed for corrugating the margin of the body blank, and which also cooperates with the inner sleeve for forming the convex flange. Fig. 12 is a top end view of the lower corrugating member. Fig. 13 is a top plan view of the stationary annular die member. Fig. 14 is an elevational view of the eccentric-driven yoke, by which the inner and outer sleeves and related parts are controlled. Fig. 15 is a broken end elevation, taken in the direction of the arrow in Fig. 6; showing the cam and related parts that 70 depress the ram 6, and Fig. 16 is a central vertical section of a milk bottle, showing the closure applied thereto.

In the preferred construction of the bottle closure, two disc-shaped blanks of any suitable paper stock, and of different diameters, as 2 and 3, are employed. The blank 2 is preferably relatively thin and tough and readily moldable, while the disc 3 is preferably of relatively thick gauge, and is practically inflexible, in order that said disc may suitably reinforce the lighter blank, and cooperate with the latter for effectually sealing the bottle mouth. The blanks 2 and 3, may be disposed in separate magazines, as 90 2' and 3', and any suitable and well-known means (shown conventionally at 2^a—3^a) may be employed for simultaneously feeding the said blanks from their magazines 95 towards the molding apparatus or die, wherein the blanks are operated upon for producing the composite cap or closure, as A, having a central two-ply disc-shaped portion a, which is arranged to seat in the usual recess of a bottle mouth (see Fig. 16), 100 and which is surrounded by an annular convex apron a', that intimately overlies and shields the flaring lip of the mouth beyond the recess, as shown in Figs. 4, 8 and 16.

A detailed description of the apparatus 105 follows:

4 represents a substantially circular base, which may be supported by a suitable table, as 4'. Upon the base 4 is mounted a hollow upright cylindrical body or casing 5, comprising a foot-flange 5', a contracted medial portion 5* having blank receiving

and cap ejecting slots 5^c—5^d, and having an expanded top portion 5^b, the free end of the latter preferably being open. The die or mold proper comprises a number of movable and stationary telescopically arranged parts, which are disposed concentrically in the casing 5, and which are timed by suitable mechanisms, to perform their several functions, by which the various steps of our methods are effected. 6 and 6' represent aligning plunger-like members or rams, which are disposed and operated axially in the body and base, and between the facing ends of which the blanks 2 and 3 are disposed and held during the construction of the closure. The rams 6—6' are independently reciprocable. The ram 6 is supported and guided partially by a piston-like member 7, and a sleeve 8, the said guides being disposed respectively in the body portions 5^b and 5^a, and being movable relatively to and independently of the ram 6. The member 7 is raised and lowered by a yoke 7', whose arms are pivoted by means of pins 7^a, which are disposed radially in suitable openings, as shown in Figs. 1, 5 and 14. The yoke 7' extends well above the casing 5 and straddles the ram 6, and its free end is formed with a horizontal opening 7^b, in which is journaled a circular crank-member 7^c, the latter being rigid upon, and rotatable by a shaft 9, which is supported by bearings 9' carried by uprights 10—10', that rise from the table 4' (see Fig. 6). One end of shaft 9 is fitted with a relatively large spur-gear 10^a, which is driven by a pinion 12, the latter being loosely supported by a stationary rod 12', which projects beyond the upright 10', and upon which is also loosely journaled a pulley 12^b, which may be driven continuously by a belt 12^c. Between the pinion 12 and the sheave 12^b is disposed a clutch member 12^d, operable by a lever 12^e by which the sheave and the pinion may be operatively connected, or released. Shaft 9 passes eccentrically through the member 7^c, as best seen in Fig. 14, and effects the variable movements of the member 7 during each molding operation.

The plunger 6 is normally held in its elevated or released position (see Fig. 1), by means of a spring 6^a, and is depressed during the molding operations by a cam 13, which is rigid on the shaft 9 and is in constant engagement with a lever 14, the latter being preferably mounted rigidly on a shaft 14', which is also supported by the uprights 10—10' (see Fig. 6). 15 represents a similar lever which is supported and rocked by the shaft 14', the free end of said lever being normally in frictional engagement with the top end of the plunger 6. During the molding operations the cam 13 is rotated constantly and each revolution effects the variable vertical movements of the plunger 6 required to produce one of the bottle closures.

16 represents a similar sleeve that surrounds and is slidable on the sleeve 8, its movements being partially controlled by the member 7, through the medium of an annular guard 7^e, which is rigidly secured to the bottom face of the member 7, by screws 7^f. The sleeve 16 is depressed directly by the tension of springs 17, (see Figs. 1 and 5), which are disposed in downwardly facing sockets 7^x of member 7, and said sleeve is also subjected to indirect depression by a spring 17', which surrounds the stem of the ram 6 and engages the counterbored top end of the sleeve 8, the latter sleeve being provided with an annular flange 8', which plays in a corresponding counterbore of the sleeve 16. By this construction or arrangement of the parts 8 and 16 either may move independently within certain limits, and either may effect the vertical movement of the other part, as may be understood by consulting Figs. 1, 2, 3 and 4.

The blanks 2 and 3 when fed from the magazines 2'—3', by horizontally movable members 2^a—3^a, pass respectively through the slotted opening 5^c, and an opening 5^e of the casing portion 5^b. The action of the said blank feeding being timed in a well-known manner (not shown), so as to simultaneously dispose the discs 2 and 3 in the cap forming cavity of the apparatus, when the plungers 6—6' and the other molding parts are in the positions shown in Fig. 1, in which the opening 5^e registers with slots 16^a and 8^a of the sleeves 16 and 8, and the slot 5^c registers with the normal gap or space between the upper and lower die members, as indicated at x, in Fig. 1. The lower portion of the sleeve 8 is counterbored at 8^b, to substantially the diameter of the smaller disc 3, as well as the diameter of the enlarged lower end 6^b of the ram 6. The disc 3 upon entering the counterbore 8^b, is received in an annular recess 8', which tends to prevent the disc 3 from gravitating towards disc 2, until the plunger 6 descends and forces said disc into the molding position shown in Fig. 2. When disc 2 enters the void x, it initially rests upon the top end of the plunger 6', where it remains until the ram 6 depresses the disc 3 to the position shown in Fig. 2. When the discs 2 and 3 are disposed axially in the die cavity, as explained, the member 7 is immediately depressed by the eccentric 7^e, as from the position shown in Fig. 1, to that shown in Fig. 2. This lowering of the member 7, supplemented by the tension of the springs 17, depresses the sleeve 16 until its corrugated lower end 16' engages and compresses the peripheral margin of the disc 2 against the corrugated top end 18', of a similar tension controlled member 18, which is resiliently held in the corrugating position shown in

Fig. 2, by bolts 18^a and spring 18^b, the latter being supported by the base 4. The gripping and corrugating of the outer margin of the disc 2, is timed to take place an instant before the plunger 6 exerts any pressure upon the disc 2, and at substantially the same instant the plunger 6' recedes downwardly, as shown in Fig. 2. This downward movement of plunger 6' is followed immediately by the lowering of the plunger 6 by the depressing effect of the portion 13' of the cam 13 (see Fig. 15), which forces the discs 2-3 into the void α' created by the recession of the plunger 6', for cupping the disc 2, as shown in Fig. 3. At the end of this cupping action the plunger 6' again starts upwardly and contacts with the underside of the disc 2. Both of the plungers then move upwardly substantially at the same speed, the pressure on the plunger 6 being slightly relaxed for the purpose, by the rotation of the cam 13 from the point 13' to the point 13^a, which effects the slight reduction of the cup of the closure A, as shown in Fig. 4. At this stage, the plunger 6 breaks contact with the closure due to the sudden relaxation of the pressure occasioned by the movement of the cam 13, from the full line to the dotted line position, shown in Fig. 15. This effects a quick upward movement of plunger 6 to the extent shown by the full lines in Fig. 4. Plunger 6 is then suddenly lowered by the point 13^c of cam 13 depressing the lever 14, and strikes a quick blow against the inner margin of apron α' of the closure, for completing the compressing and molding of said margin upon the outer margin of the disc 3, as shown in the sectional view in Fig. 1. As the said blow is struck by plunger 6 the latter, due to the contact of the portion 13^d of the cam 13 with the lever 14, is finally raised by the tension of spring 6^e to the position shown in Fig. 1, ready to start the molding of the next closure, and so on. Immediately the plunger 6 strikes the final blow, as explained, the member 7 is lifted by the crank 7^e towards the idle position shown in Fig. 1. This relaxes the tension of springs 17-17', and allows the guard 7^e to raise the sleeves 16 and 8 to their full release position (see Fig. 1).

The plunger 6, is controlled mainly by cam 19 which is preferably disposed beneath the table 4' and is mounted upon and driven by a shaft 19' which is supported by depending bearings 4^a. One end of shaft 19' is fitted with a bevel gear 20 which meshes and is driven by a similar gear 20' the latter being mounted on the lower end of a vertical shaft 20^a. Shaft 20^a is driven by power transmitted by the shaft 9 and bevel gears 21-21' which are mounted respectively upon the said shafts (see Fig. 6).

At the start of the cupping operation,

(see Fig. 3), the sleeve 8 is moved downwardly, and its concave lower end 8^c, forces the corresponding portion of the disc 2 against the beaded top end 22', of a stationary tubular member 22, and begins the convex molding of the flange α' of the closure. During these operations the sleeve 8 is resiliently held by the spring 17'. The tension of spring 17', as well as that of the springs 14, is so regulated that when the cupping of the disc 2 is effected, as shown in Fig. 3, the annular portion of disc 2 beyond the perimeter of disc 3 is forcibly drawn or moved radially between the sleeves 8 and 16 and the lower die members 18 and 22, thereby contracting the disc 2, to the extent shown by comparing Fig. 7 with Fig. 8. The sleeve 8 maintains its resilient grip of the flange α' , while the plunger 6' is forcing the cupped portion upwardly, and this upward movement of plunger 6', owing to the resilient grip of the parts 8, 16, 18 and 22 effects the inward folding of the inner margin of the flange α' , upon the disc 3, as shown in Figs. 1 and 4, the said fold being compressed and clinched by the final sharp quick blow of the plunger 6, as explained, for the purpose of effectually interlocking the said discs, and completing the formation of the closure, as shown in Figs. 1, 4, and 8. The finished closures are usually ejected as shown at the left in Fig. 1 by an air blast in a well-known manner (not shown).

The apron α' of the closure remains partially in the grip of the corrugating member until the inward folding of the apron upon the disc 3 is effected. This latter operation so contracts the disc 2 radially, as to entirely free the apron from the corrugated faces of the members 16-18, as shown in Fig. 4, in which the apron is shown still gripped by the sleeve 8 and the stationary die member 22, as well as by a curved portion 16^c of the sleeve 16, which cooperates with the other parts for finally pressing and effacing the corrugations previously formed in the margin of the apron. The dotted line 6^x in Fig. 4 indicates the position of the plunger 6, when the sharp clinching blow referred to is struck.

Having thus described our invention, what we claim, is—

1. The method of making bottle closures which consists of imposing a substantially inflexible disc concentrically upon a larger thinner and pliable disc, then resiliently clamping the extended annular margin of the larger disc, then depressing and cupping the larger disc to the extent of the diameter of the smaller disc while said clamping is maintained, then molding said extended margin convex, partially folding the said extended margin upon the smaller disc, and finally compressing and clinching the said fold.

2. The method of making bottle closures, which consists of corrugating the peripheral margin of a relatively large disc of thin tough paper, then superposing concentrically 5 upon said disc a relatively thick inflexible reinforcing disc, then depressing said discs and forming a concentric cup having a depth greater than the combined thickness of the two discs, reducing the depth of the cup 10 and effecting the inward folding of the portion of the larger disc that extends beyond the smaller disc upon the latter disc, and finally compressing and clinching the said infold and interlocking the two discs.
- 15 3. The method of making a flexible bottle closure, which consists of corrugating the peripheral margin of a relatively large pliable paper disc, then superposing concentrically thereupon a smaller and thicker inflexible disc, then cupping the portion of the larger disc overlayed by the smaller disc, and molding the contracted annular outer portion of the larger disc convex, then folding the inner margin of said annular portion upon the smaller disc for interlocking 20 said discs, and finally applying pressure upon the convex portion of the large disc for effacing the said corrugations.
- 25 4. An apparatus of the class described, comprising in combination a casing, a pair of aligning plunger-like die members reciprocable axially in said casing, means for feeding disc-shaped blanks of paper stock of different diameters into said cavity between the facing ends of said plungers, means for moving one of the plungers toward the opposing plunger for bringing said discs together concentrically, means for resiliently gripping and corrugating the 30 peripheral margin of the larger disc, means for depressing said plungers for cupping the larger disc while the said margin remains in the grip of the corrugating means, means for reversing the movement of said plungers 35 for effecting the inward folding of a portion of said corrugated margin upon the peripheral margin of the smaller disc, for interlocking said discs.
- 40 5. An apparatus for making bottle closures, comprising a hollow body having spaced openings for the entrance of paper discs of different diameters, means for feeding said discs separately towards said openings, independently reciprocable plungers 45 disposed axially in said casing, said plungers being spaced apart to receive said discs, means for depressing the uppermost plunger for imposing the smaller disc upon the larger disc, means for gripping and corrugating the outer margin of the larger disc, means for again depressing the uppermost 50
- plunger for cupping the central portion of the larger disc to the extent of the diameter of the smaller disc while the corrugating members yieldingly grip the said annular portion, means for convexing the said corrugated portion for forming a flexible apron surrounding said cupped portion, means for moving the lowermost plunger upwardly for reducing the cup of said large disc and for 55 effecting the folding of the inner margin of said apron upon the peripheral margin of the smaller disc, and means for reciprocating the uppermost plunger for compressing and clinching said inward fold for interlocking said discs.
- 60 6. An apparatus of the class described, comprising a hollow casing provided with receiving and ejecting openings, means for feeding circular blanks of paper stock towards said receiving openings, similar aligning plunger-like die-members disposed axially in said casing and independently reciprocable, means for moving one plunger towards the other plunger for imposing the smaller blank concentrically upon the larger blank, a sleeve surrounding the uppermost plunger, a stationary tubular die-member below and registering with said sleeve, tension means for moving said sleeve towards the stationary member and for convexing the margin of the larger blank that extends beyond the smaller blank, a second sleeve telescoping the first sleeve, the lower end of the second sleeve being provided with corrugating teeth, a third sleeve telescoping said stationary member having corresponding corrugating teeth formed in its upper end adapted to cooperate with said second sleeve for crimping or corrugating the outer margin of the larger blank, tension means for holding said third sleeve in the corrugating position, means for simultaneously moving said plungers downwardly for cupping the central portion of the larger blank, 65 means for increasing the tension of said first sleeve for effacing said corrugations and for effecting the final molding and smoothing of said convex portion of the larger blank, means for effecting the folding of the inner margin of the convex portion for interlocking said blanks, and means for relaxing the tension of said movable sleeves and for raising the uppermost plunger and the uppermost sleeve away 70 from the molding position, substantially as shown and described.
- 75 In testimony whereof we affix our signatures.
